SAFETY GUARD FOR POWER PRESSES

Filed June 1, 1926

Fig 2.

UNITED STATES PATENT OFFICE

WALTER O. WILL AND ERIC CARLSON, OF CHICAGO, ILLINOIS, ASSIGNEES TO STEWART MANUFACTURING CORPORATION, OF CHICAGO, ILLINOIS, A CORPORATION OF DELAWARE

SAFETY GUARD FOR POWER PRESSES

Application filed June 1, 1926. Serial No. 112,865.

The purpose of this invention is to provide a safety device for attachment to punch presses for preventing the hands of the operator from becoming involved between the 5 punch and die in the operating stroke of the punch. It consists in the elements and features of construction shown and described, as indicated in the claims.

In the drawings:—

10 Figure 1 is a side elevation of a punch press equipped with this invention, the upper and lower part of the press being broken away to condense view.

15 Figure 2 is a front elevation of the same upon a larger scale.

Figure 3 is a similar view showing the parts embodying the invention in a different position from that of Figure 2.

20 Figure 4 is a section at the line 4—4 on Figure 2.

In the construction shown in the drawings, the standard of a punch press is indicated at 10. The bed of the press upon which the die is to be mounted is indicated at 11. 12, 25 12 are similar brackets rigidly secured to the fixed head of the press standard indicated at 13, and projecting forwardly from said head past the path of reciprocation of the punch-carrying press head which is indicated at 15. 30 Upon the press head there is mounted a rack bar, 16, having at its opposite edges parallel racks, 16^x, 16^x, which engage respectively gear segments, 17, 17, having rock shafts, 18, 18, journaled as hereinafter more particularly 35 described upon the brackets, 12, 12, respectively above the zone of normal position and movement of the operator's hands and arms in attending the press. Each of the segments, 17, 17, carries a fender arm, 19, which is 40 mounted for vertical adjustment as herein-after more particularly described in the segment, said fender arms, 19, 19, extending down and toward each other at their position of rest in front of the path of cooperation of 45 the punch and die, that is to say, between the position of the operator facing the press and the path of movement of the punch, said fender arms at their free ends standing, at 50 their meeting position, substantially across the plane of meeting of the punch and

die; so that said fender arms, 19, project between the position of the forearms, or between the hands, of the operator manipulating the metal between the punch and die. At this rest position of the fender arms, the 55 gear segments, 17, 17, are meshed at their lower ends of their respective arcs with the respectively facing racks, 16^x, 16^x and in the descending operating stroke of the reciprocating press head, it will be seen that the rack, 60 16, actuates the segments for rocking them in their journal bearings in the direction for spreading the fender arms, 19, 19, at their free ends which stand between the forearms of the operator; whereby the operator's 65 hands will be forcibly withdrawn from position at which they would be liable to be involved between the punch and die in the completion of the operating stroke of the punch.

Details of the construction will now be described.

The brackets, 12, 12, constitute parts of a rigid and substantially unitary frame which is carried rigidly on the fixed head, 13, said frame comprising said brackets and a transverse bar, 12^a, which connects them at their forward ends, said bar being welded to said forward ends of the brackets. At the lap and junctions of said transverse bar, 12^a, with the brackets, 12, there are secured rigidly to both said lapping parts by welding thereto, journal bearings, 12^b, 12^b, for rock shafts, 18, 18, of the segments, 17. Each of the segments, 17, has formed integrally with it at the outer side of the rock shaft, a sleeve, 17^b, for receiving the upper straight portion, 19^a, of the fender arm, 19, said fender arm being threaded at said straight portion for adjusting and stop nuts, 20, 20, applied on said threaded portions respectively, above and below the 80 sleeves, 17^b, the ends of said sleeves being counter-bored for seating the nuts, which are tapered at their inner ends for so seating at the ends of the sleeves. This expedient, it will be seen, constitutes means for adjusting the fender arms, 19, up and down to vary the position of their free end portions which are to guard the hands of the operator. Said free end portions of the fender arms, 19, are preferably flexed in curved 95 100

form concave outwardly, that is, toward the arms of the operator; and subtending the curves at the concave side, there is mounted upon each fender arm a strap, 21, of suitable material such as leather for uninjurious encounter with the arm or hand of the operator in the spreading movement of said guard fender arms, 19.

For inclosing the operating mechanism comprising the segments, 17, for safety, against engagement of the fingers of the operator or bystanders between the rack and said segments, there is provided a casing, 25, of a comparative light sheet metal formed of a blank having lateral lugs, 26, 23, folded at right angles to the plane of the blank forming bracket arms spaced apart by the transverse dimension of the blank, and thereby positioned for lapping outside the brackets, 12, 12, respectively. The central or main body of the blank constituting the front plate of the casing has bayonet-slot apertures, 28, 28, and the structure comprising the brackets, 12, is furnished with headed means for engaging the bayonet-slots, the heads passing through the large portion of the slot and the reduced portion back of the heads engaging the narrow portion of the slot when the casing is applied in the obvious manner. In the construction as shown, the headed means for engaging the bayonet-slots is afforded by the rock shafts, 18, of the segments, 17, respectively, said rock shafts being terminated at their forward ends as seen with heads, 18^a, back of which the rock shafts are reduced in diameter, as indicated at 18^b. The casing is further adapted to be secured to the brackets by bolts, 27, 27, taking through apertures in the lateral lugs, 26, into the brackets 12.

40 We claim:—

1. In a power press having a bed for holding a die, a fixed head and a reciprocating head, a device for the purpose indicated comprising a pair of parallel racks mounted on the reciprocating head of the press; segment gear members pivoted on the fixed head of the press for meshing with the respective racks; fender arms mounted on the segments gear members respectively and extending in general up and down at the rest position of the reciprocating head with their lower parts deflected inwardly toward each other and substantially meeting in front of the position of a die on the bed, the segment gear members being angularly dimensioned with respect to the stroke of the reciprocating head of the press for spreading said fender arms during the down stroke of the reciprocating head widely and in excess of the width of the press.
2. In a power press having a fixed bed, a fixed head and a reciprocating head, a pair of parallel racks mounted on the reciprocating head, segment gear members pivoted on the fixed head of the press at opposite sides

of the path of the reciprocating head and meshing with the respective racks, said segment gear members having adjacent their pivots respectively vertical slideways, fender arms having straight upper end portions engaged in said slideways, respectively, and having their lower end portions deflected obliquely toward the medial vertical plane of the path of the reciprocating head, and means for adjusting the fender arms longitudinally of their straight portions in their respective slideways.

3. In the construction defined in claim 2, the upper end portions of the fender arms being straight and the segment gear members having slideways in which said straight portions may be adjusted longitudinally, said straight portions being exteriorly screw-threaded and having each a longitudinal groove for receiving a key to hold said fender arms nonrotatably in the slideways, a key engaging each of the grooves of said slideways, and nuts on the threaded portions of the fender arms adapted to be set up against the opposite ends of the slideways, whereby they serve for adjusting the fender arms longitudinally and securing the latter in adjusted position in the slideways.

In testimony whereof, we have hereunto set our hands at Chicago, Illinois, this 28th day of May, 1926.

WALTER O. WILL.
ERIC CARLSON.
